UNITED STATES PATENT OFFICE.

ADOLPH F. STOELTING, OF KIEL, WISCONSIN.

MILK-VAT.

No. 893,883.

Specification of Letters Patent.

Patented July 21, 1908.

Application filed April 16, 1908. Serial No. 427,475.

To all whom it may concern:

Be it known that I, ADOLPH F. STOELTING, of Kiel, Wisconsin, have invented a Milk-Vat, of which the following is a specification.

5 This invention relates to a vat such as is used for heating milk in the process of making cheese and my object is to provide an improved joint for the seams of such a vat which will be stronger and at the same time 10 simpler than those heretofore used in this character of vat. I further design to provide an improved outlet which will have the advantage of strength and simplicity.

My invention may best be understood 15 from a consideration of the following description of one form thereof taken in connection with the accompanying drawings, wherein,

Figure 1 is a plan view of the vat embodying my invention. Fig. 2 a longitudinal section therethrough. Fig. 3 is a transverse section on the plane 3. Fig. 4 is a bottom plan view of the center-joint on an enlarged scale. Fig. 5 is a transverse section therethrough taken on the plane 5. Fig. 6 is a 25 plan on an enlarged scale of the outlet casting and joint, the end-sheet being omitted. Fig. 7 is a front elevation of the same. Fig. 8 is a perspective view of one of the center-joint castings. Fig. 9 is a perspective of the outlet casting. Fig. 10 is a front elevation of an alternative form of outlet casting for use in flat-bottom tanks having no center seam; and Fig. 11 is an enlarged transverse section 30 through the center of the bottom of the vat 35 on the plane 11.

In these drawings every reference letter and numeral refers always to the same part.

The vat, which in its general form is in common use, comprises in its construction 40 an external or water-holding vat A supported on posts B at the sides, and transversely by means of wooden girths C. The vat A is of rectangular form and may be made in any preferred manner, not being a part of my 45 invention. On its upper margin is a rectangular wooden frame D, on which rests the marginal flange e' of the inner or milk-vat E, which is likewise rectangular in form and is made up in four side and bottom sheets e², 50 united together by a longitudinal seam e³ and a transverse seam e⁴, both of which constitute a part of my invention, being specially formed as will be presently described, also two end-sheets e⁵ united to the sheets e² along the

end-angles of the vat. It will be understood 55 that when the vat E is still empty and water run into the tank A, the upward pressure of the water on the bottom of said tank E will cause it to bulge upwardly unless supported, and to this end I provide transverse beams 60 made up of channels F and wooden strips G which are secured on the ends of upright ribs H at intervals along the tank, and longitudinal planks I are interposed between said beams and the bottom of the tank E where- 65 by the latter is supported against internal pressure.

It has been a difficult matter to get a solid form of joint for the seams e³ and e⁴, subjected as they were to considerable variations 70 of pressure and to alternate internal and external bulging stresses; wherefore I have sought to provide a tighter and stronger form of joint than the old flanged riveted joint heretofore used. Such a joint requires 75 considerable longitudinal stiffness in order to maintain itself tight, and I have found that the flanged joint does not offer sufficient stiffness owing to its liability to buckle, which in turn causes opening of the seam be- 80 tween the rivets.

As best seen from Fig. 5, in my joint I provide one of the meeting-sheets e² with a fastening-flange e⁶, and the other with a U-shaped bend e⁷ enveloping the flange e⁶; and 85 I further prefer to reinforce the joint by inserting between the flange e⁶ and bend e⁷ a U-shaped strap of sheet-metal e⁸, thereby so thickening the joint as a whole as to make it practically impossible for the joint to buckle. 90 The joint is finished by rivets e⁹ passing through all the laps thereof at sufficiently frequent intervals, and hermetically sealed by pouring in solder. The full lengths of the seams e³ and e⁴ are thus constructed along 95 the bottom, except at their point of intersection, where an additional reinforcing means is necessary, and means enabling the crossing of the two joints to be effected without leakage at that point. To this end I introduce a 100 pair of castings J of T-shape as shown in Fig. 8, the central leg of the T being divided longitudinally by a slot or saw-cut j' extending nearly to the outer face j². All four limbs of the T thus formed are of an angle-shaped 105 section, as clearly shown in the drawing, the upper surface being flat, and are provided with rivet holes j³ suitably spaced along the

side-faces thereof. These two members J are secured on opposite sides of the longitudinal seam e^3 as shown in Fig. 4, the ends of the seams e^4 being first inserted into the 5 slots j' with the sheets e^2 projecting over the face j^2 to form the seam e^3 ; and when thus inserted, the two arms j^4 are brought together by riveting through the holes j^3 and clamping them so as to tighten the seam and 10 reinforce the same. Then, the longitudinal seams e^3 being formed, the two members J are brought together with the faces j^2 opposed and the whole riveted together by rivets e^9 passing through the holes j^3 . 15 When this is done the joint will be rigid and nonleakable. In order to further strengthen the seams, especially the longitudinal seam e^3 , I provide a plurality of hook-bolts M which engage in holes e^{10} in the seams, and 20 passing through suitable apertures in the channels F are secured by means of nuts m' , on the under side thereof, holes g' being made in the beams G for this purpose, as clearly shown in Fig. 11.

25 In the case of my improved outlet I provide an outlet-casting K, Fig. 9, which has a flange k' on one end adapted to abut upon the end-sheets e^5 at one end of the vat, and to be secured thereto by rivets k^2 passing 30 through holes k^3 therein. The casting K has a tubular threaded portion k^4 which also passes through a hole in the outer vat A and is nonleakably secured thereto by means of two nuts M which engage the screw-thread 35 thereof and clamp the margin of the hole in the vat A between them. From the face of the flange k' projects a long bracket-arm k^5 which is divided in the center by a slot k^6 adapted to receive the end of the seam e^3 in 40 the same manner as the slot j' receives the seam e^4 , the two limbs of the bracket-arm k^5 being then hammered together and connected by rivets, and the whole soldered over. The face k' has a groove k^7 therein along the 45 junction of the projection k^5 for the seam between the pieces e^2 and e^5 of the vat. It will be clear that the casting K forms a most strong and convenient manner of arranging the outlet so that there shall be no leakage 50 between the outlet and the vat.

In some cases it will not be necessary or desirable to have a longitudinal seam e^3 , and where this latter is omitted I may use the outlet casting without any central slot k^6 in 55 the form K', as shown by Fig. 10. I may also make various other changes and variations in the construction without departing from the spirit of this invention, as will be readily understood by those skilled in the 60 art.

Having thus described my invention, what I claim as new and desire to secure by Letters Patent is:

1. In a sheet-metal milk-vat, a seam be-

tween sheets of metal for the bottom thereof 65 comprising a flange formed on the edge of one sheet by bending an edge-strip thereof at right-angles, a U-shaped bend formed on the edge of the adjacent sheet and embracing said flange, and rivets securing the whole together. 70

2. In a sheet-metal milk-vat, a seam between sheets of metal for the bottom thereof comprising a flange formed on the edge of one sheet by bending an edge-strip thereof at 75 right angles, a U-shaped bend formed on the edge of the adjacent sheet and embracing said flange, a U-shaped metal strip inserted between said flange and bend, and rivets passing through all five laps of said seam and 80 securing them together.

3. In a sheet-metal milk-vat, a seam between sheets of metal for the bottom thereof comprising a flange formed on the edge of one sheet by bending an edge-strip thereof at 85 right angles, a U-shaped bend formed on the edge of the adjacent sheet and embracing said flange a U-shaped metal strip inserted between said flange and bend, and means securing the several laps of the seam rigidly together. 90

4. In a sheet-metal milk-vat, a seam between sheets of metal for the bottom thereof comprising a flange formed on the edge of one sheet by bending an edge-strip thereof at 95 right-angles, a U-shaped bend formed on the edge of the adjacent sheet and embracing said flange, a pair of rigid bars of angle-shaped section set in the angle between each sheet and the seam, and rivets passing 100 through the seam and bars and securing the whole rigidly together.

5. In a sheet-metal milk-vat, a seam between sheets of metal for the bottom thereof comprising a flange formed on the edge of one sheet by bending the edge-strip thereof at right angles, a U-shaped bend formed on the edge of the adjacent sheet and embracing said flange, a U-shaped metal strip inserted between said flange and bend, a pair of rigid 105 bars of angle-shaped section set in the angles between each sheet and the seam, and rivets passing through the seam and bars and securing the whole rigidly together. 110

6. In an apparatus of the class described, 115 in combination with sheets having intersecting seams which stand at right angles to the plane of the sheets, reinforcing-means for said seams at the point of intersection comprising rigid stiffening bars of angle-shaped 120 section which are located in the angles between the sheets and seams on all sides of the latter, and rivets passing from side to side of the seams through said stiffening-bars and securing the whole together. 125

7. In an apparatus of the class described, in combination with sheets having intersecting seams which stand at right angles to the

plane of the sheets, reinforcing-means for said seams at the point of intersection comprising rigid stiffening bars of angle-shaped section which are located in the angles between the sheets and seams on all sides of the latter, rivets passing from side to side of the seams through said stiffening-bars securing the whole together, and solder hermetically uniting the whole together.

5 8. In an apparatus of the class described, in combination with metal-sheets having seams intersecting substantially at right angles, said seams comprising flanges standing at right-angles to the plane of the sheets, a 10 pair of stiffening-members each having a **T**-shaped form and the center-leg of each **T** being slotted and receiving the end of one of the seams in the slot thereof, and rivets passing through the two branches of said leg and 15 the seam and securing the whole together; the two outer faces ($\frac{1}{2}$) of the respective **T**s lying on opposite sides of the other seam; and rivets passing through said faces and seam 20 and securing the whole together.

25 9. In an apparatus of the class described, in combination with metal-sheets having seams intersecting substantially at right angles, said seams comprising flanges standing at right-angles to the plane of the sheets, a 30 pair of stiffening-members each having a **T**-shaped form, the center-leg of each **T** being slotted and receiving the end of one of the seams in the slot thereof, and rivets passing through the two branches of said leg and 35 the seam and securing the whole together; the two upper faces ($\frac{1}{2}$) of the respective **T**s lying on opposite sides of the other seam, and rivets passing through said faces and seam 40 and securing the whole together, and a fusible alloy hermetically uniting the several sheets and seams and stiffening pieces.

45 10. In combination with an outer vat and an inner vat, an outlet member of tubular form united to said inner vat and passing through a hole in said outer vat, and means for hermetically sealing the hole in said outer vat in a removable manner; said outlet member having an arm projecting under and united to the bottom-sheet of said vat.

50 11. In combination with an outer vat and an inner vat, an outlet member of tubular form united to said inner vat and passing through a hole in said outer vat and means for hermetically sealing the hole in said outer vat in a removable manner; said outlet member having an annular face united to the end-sheet of said vat and a bracket-arm projecting under and united to the bottom-sheet of said vat.

55 60 12. In combination with an outer vat and an inner vat, the latter having a seam along the bottom thereof, a tubular outlet-member hermetically united to said inner vat and projecting through a hole in said outer vat 65 and hermetically united thereto in a tempo-

rary manner said outlet-member having an annular face hermetically united to the end-sheet of said inner vat and a bracket-arm projecting from said face end and united to the bottom of said inner vat; said bracket-arm being longitudinally slotted to receive the flange of said seam, and rivets passing from side to side through said bracket-arm and seam and rigidly uniting the whole together.

70 75 13. In combination with an outer vat and an inner sheet-metal vat, said inner vat having a longitudinal central seam and a hole in the end-sheet opposite the end of said seam; a tubular outlet member having an annular face hermetically secured to the end-sheet around the hole thereof, and a screw threaded tubular portion passing through a hole in the end of said outer vat; and a pair of nuts on said screw-threaded portion clamping the edge of the hole in said outer vat between them and forming a temporary hermetic joint; said outlet member having further a bracket-arm extending from said annular face beneath the bottom of said inner vat, 90 said bracket-arm being longitudinally slit; said longitudinal seam comprising a rectangular flange on the edge of one sheet and a **U**-shaped bend on the other, the whole forming a rectangularly extending flange which is 95 received in the slit of said bracket-arm; and rivets passing through said arm and seam from side to side and uniting the whole rigidly together.

100 14. In a milk-vat, the combination of a seam between sheets of metal for the bottom thereof comprising a flange formed at right-angles to the plane of said bottom, a fixed object below said seam, and a hook-bolt engaging a hole in said seam and secured to said 105 fixed object.

15. In a milk-vat, in combination with a sheet-metal bottom, having a longitudinal seam at right angles to the plane of said bottom, a transverse beam below said bottom, 110 and a hook-bolt engaging in a hole in said seam and secured to said beam.

16. In a milk-vat, in combination with a sheet-metal bottom therefor having a longitudinal seam between the edges of the sheets, 115 said seam comprising overlapping folds on the edges of the sheet, a fixed object below said seam, and means passing through said seam and securing it to said fixed object.

17. In a milk-vat, in combination with a sheet-metal bottom therefor having a longitudinal seam between the edges of the sheets, 120 said seam comprising overlapping folds on the edges of the sheet, a transverse beam secured to said vat below the bottom thereof, 125 and means passing through said seam and secured to said beam.

18. In a milk-vat, in combination with a sheet-metal bottom therefor having a longitudinal seam between the edges of the sheets, 130

said seam comprising overlapping folds of the edges of the sheet, a transverse beam secured to said vat below the bottom thereof, and a hook-bolt engaging a hole in said seam and having a shank passing through a hole in said beam and a nut on the lower side of the latter.

In witness whereof, I have hereunto set my hand this 11th day of April, 1908.

ADOLPH F. STOELTING.

Witnesses:

RICHARD KIEL,
M. E. SURPLICE.
